INJECTION PUMP

Patrick C. Ward, San Francisco, Calif.

Application April 9, 1948, Serial No. 19,948

6 Claims. (Cl. 123—140)

1

This invention relates to a fuel injection pump for an internal combustion engine, more particularly, a Diesel engine, and to an electrical system for controlling the pump and governing the speed of the engine.

In the ordinary fuel injection system of a Diesel engine, there is provided a high pressure reciprocating pump, which is actuated by a cam keyed to or actuated by the crank shaft of the engine. In one such system the stroke of the pump piston is varied to govern the amount of fuel injected into the engine; hence, the speed and power output of the engine. Such variations of stroke of the pump piston is accomplished by various means; for example, a beveled cam may be used, and the cam shifted perpendicularly to the axis of the pump piston so as to present different points of the cam to the piston, thereby altering the stroke of the piston.

This and other mechanical systems of controlling the feed of fuel to a Diesel engine or the like are objectionable, in that adjustable parts, such as the above-mentioned beveled cam, are subject to wear, develop play and require frequent adjustment and repair in usage.

It is an object of this invention to provide an improved means of controlling the supply of fuel to a Diesel or other internal combustion engine.

It is a further object of the invention to provide a system for governing the supply of fuel to a Diesel engine or the like, which avoids or minimizes the employment of mechanical elements which develop wear and play during usage and require frequent repair.

It is a further object of the invention to provide an electrical system for governing the speed or power output of a Diesel engine or the like, whereby an ordinary, constant stroke reciprocating fuel pump may be used, and whereby the supply of fuel is accurately and rapidly responsive to the load on the engine.

It is a still further object of the invention to provide an electrically governed fuel feed system for a Diesel engine or the like, which measures the fuel input by displacement, and whereby the fuel displacement is rapidly and accurately responsive to the load or to a rheostat or the like.

These and other objects of the invention will be apparent from the following description and the ensuing claims.

The invention will be better understood by reference to the accompanying drawings, in which one form which the invention may assume is shown.

2

Referring now to the drawings:

Figure 1 is a view of both the mechanical and electrical elements of the fuel injection system of the invention, showing the mechanical or pump element in cross-section and the electrical system diagrammatically.

Figure 2 is a fragmentary, cross-sectional view of the top portion of the pump element, showing an alternative structure for regulating the air pressure at the head of the pressure regulator cylinder.

Referring now to Figure 1 of the drawings, a pump element 1 is formed in a housing 2, which is suitably bolted to the framework of the engine (not shown). The pump proper, identified generally as 3, is shown as a conventional high pressure, reciprocating fuel injection pump comprising a piston 10 reciprocable within a cylinder 11. The piston is normally urged downwardly by a coil spring 12 encircling the lower end of the piston and compressed between the pump housing and a retainer 13 formed on the lower end of the piston. The piston 10 is reciprocated in the usual manner by a cam 14 having a high point 15 and keyed to a cam shaft 16 which, in turn, is operatively connected to the crank shaft of the engine (not shown). The pump is also provided in the usual manner with a fuel supply line 20 containing a check valve 21. The valve 21 is normally held in closed position against the pressure of the fuel by a coil spring 22 encircling the valve stem and compressed between the valve head and a plug 23 in threaded engagement with the pump housing. The pump 30 is also provided with a fuel feed duct 24, which is normally closed by a check valve 25 under the tension of a coil spring 26 encircling the valve stem and compressed between the valve head and a hollow plug 27 threaded into the pump housing. A fuel feed line 28 communicating with the feed duct 24 leads to the engine cylinders or manifold in the usual manner.

Formed in the pump housing, to the left of the pump proper as viewed in Figure 1, is a pressure regulator cylinder 35 having a downwardly extending portion 36 concentric with the regulator cylinder and of smaller diameter, said concentric portion being referred to hereinafter as the displacement cylinder. Also formed in the pump housing, concentrically with respect to the regulator cylinder 35, is an annular space or chamber 37 to receive a solenoid coil 38, as and for the purpose explained hereinafter. Disposed within the regulator cylinder so as to be reciprocable therein is a pressure regulator piston 39

constructed of iron or other suitable material of high magnetic susceptibility, and depending from and secured to the regulator piston is a displacement piston 40 which is reciprocable within the displacement measuring cylinder 36. The regulator piston 39 is normally urged downwardly to a closed position, as shown, so as to bear against a washer 41, by a coil spring 42 compressed between the top of the regulator piston 39 and the head of the measuring cylinder 35. An adjusting screw 43 is provided at its lower end with a spring retainer 44 to bear against the coil spring 42, and with a lock nut 45. By loosening the lock nut 45, the tension of the coil spring 42 can be adjusted as desired. The regulator piston 39 is provided with longitudinal ducts 46 for return of oil or fuel which may leak into the space above the piston.

A fuel duct 50 is formed in the pump housing, and a branch duct 51 leads therefrom to a recess 52 formed in the housing and closed off at its lower end by a plug 53. A port 54 communicates the recess 52 with the displacement cylinder 36. The port 54 is normally closed by a check valve 55, which is urged downwardly into closed position by a coil spring 56 encircling the valve stem and compressed between the pump housing and a retainer 57 secured to the lower end of the valve stem.

Referring to Figure 2 of the drawings, the regulator piston 39a is a solid piston, having no ducts 46 therethrough. A duct 150 is provided near the head of the cylinder 35, and a tube 151 is threaded or otherwise secured in the outer end of this duct. The opposite end of the tube 151 is threaded into a duct 152 formed in a cylinder 153. A solid piston 154, reciprocable within the cylinder 153, is provided with a peripheral slot 156 adapted to register with an air escape duct 157 formed in the cylinder. An air outlet tube 158 is threaded into the duct 157. The piston 154 is urged downwardly to align the slot 156 and duct 157, by a coil spring 165 compressed between the top of the piston and an adjustable bolt 166. An inwardly opening check valve 167 is also provided for intake of air.

It will be seen that, when the pressure in the space above the regulator piston 39a rises above a predetermined value, the piston 154 will be urged upwardly to align the slot 156 with the duct 157, thus allowing escape of air; and that when such pressure falls below a predetermined value, air will enter the regulator cylinder 35 through the check valve 167.

Mechanically, the operation of the fuel injection system, thus far described, is as follows: Fuel is supplied to the engine in the usual manner through the supply line 20, check valve 21, pump cylinder 11, feed duct 24, check valve 25 and feed line 28. With the regulator piston 39 closed as shown in Figure 1, a maximum amount of fuel drawn into the pump cylinder 11 on the downstroke of the piston will be pumped through the supply line 28 to the engine. However, the downward forces exerted on the regulator piston 39 by the coil spring 42 and the solenoid 38 are opposed by the pressure or force of the pump piston 10 on its upstroke, this opposing pressure being transmitted to the displacement and regulator pistons 40 and 39 through the liquid fuel in the ducts 50 and 51 and the recess 52.

During the return or downstroke of the pump piston 10, the downward forces exerted by the coil spring 42 and the solenoid 38 will be un-

opposed, thus returning the regulator piston to a lower position. The displacement piston 40 thus tends to reciprocate with the pump piston 10. It will thus be seen that, depending upon the balance of downward forces exerted by the coil spring 42 and the solenoid 38 and the upward force of the pump piston 10, more or less fuel drawn into the pump cylinder 11 on the downstroke will be merely pumped back and forth, or recirculated between the pump cylinder 10 and the displacement cylinder 36 via the ducts 50 and 51. The proportion of fuel intake thus recirculated is, of course, not effective in operating the engine. It will also be apparent that a maximum of fuel is supplied to the engine when the downward forces of the coil spring 42 and the solenoid 38 are greater than the maximum pressure of the pump piston 10 so as to maintain the regulator piston 39 always in closed position. Conversely, the more greatly the pump piston pressure exceeds the combined spring-and-solenoid pressure, the less fuel will be supplied to the engine. The means of regulating the relationship between these opposed forces will now be explained in detail.

The main elements of the electrical control or governing system are a conventional battery 65, starting relay 66 and motor starter-generator 67; a governor generator 68, any desired number 30 of speed regulating relays 69 and the solenoid coil 38 referred to above. As shown in Figure 1, and for purposes of varying the speed and power output of an engine employed in a vehicle or the like, there is provided a manually operable 35 rheostat 70 for varying the speed and power output of the engine. It will be obvious, however, that for purposes of a stationary engine intended to operate, say, at constant speed, the rheostat 70 may be eliminated.

The starting relay 66 is provided, in the usual manner, with contact elements 71, a closing coil 72 and a holding coil 73, and the starter-generator 67 is provided in the usual manner with an armature 74, a commutator field winding 74a and a 45 field winding 75. Likewise, the governor generator 68 is provided with a field winding 76, an armature 77 and a commutator field winding 77a. Each of the speed regulating relays 69 is provided with contact elements 78, a closing coil 50 79 to close the contact elements and a dropout coil 80, wound in opposition to the closing coil so as to urge the contact elements 78 to open position.

The rheostat 70 is enclosed in a housing 84 55 of any suitable electrically conducting material, and it is provided interiorly with a resistor 85 having spaced contact buttons 86 carried by a shelf 87 supported within the housing as shown. A slide rod 88 is provided, to which is secured a contactor 89 formed of spring metal. The slide rod 88 is also provided, as shown, with a stop collar 90, a coil spring 91 to urge it outwardly, a head 92 to compress the spring 91 and provide a bearing surface for the operator's foot or hand, 65 and a ground ribbon 93 secured at one end to the outer end of the slide rod and at its opposite end to the rheostat housing at 94. The rheostat housing 84 is also provided with insulation bushings 95.

The circuits involved are as follows: The usual 70 battery-generator circuit is employed, the battery 65 being connected by its negative terminal to ground through a lead 101 and by its positive terminal through a lead 102, a main switch 104 and a lead 105 to the closing coil 72 of the start-

ing relay 66. Also, as in the usual circuit, the opposite terminal of the closing coil is connected through a lead 106 to ground, and a push button switch 107 is provided in the lead 106; the holding coil 73 is connected to one terminal of the contact element 71, the opposite terminal of which is connected to the lead 105, as shown; the opposite terminal of the holding coil 73 is connected through a lead 108 to the field winding 75 of the starter-generator 67 (also to the field winding 76 of the governor generator 68 for a purpose explained hereinafter); and the commutator field winding 74 is connected by leads 109 and 110 to the contact element 71 and by a lead 111, to ground, as shown.

A lead 116 connects the battery-generator circuit in parallel to one terminal of each of the contact elements 78 of the speed regulating relays 69, while the opposite terminals of each of these contact elements are connected in parallel, by leads 117, to a voltage proportioning resistor 118. Branch leads 119 connect the resistor 118 with a lead 120, which connects with one terminal of the solenoid coil 38. The opposite terminal of the solenoid is shown as being connected by a lead 121 to ground, but it is obvious that, instead, the lead 121 may connect with a second solenoid coil housed in a second pump unit, and that any desired number of pump units, each having a solenoid coil, may be connected in series.

It will be apparent that, when the main switch 104 is closed, current will tend to pass through the lead 116, the relay contact elements 78, etc., to the solenoid coil 38. Normally, however, the contact elements 78 are open, as shown, and the means provided for closing them to energize the solenoid, is as follows: A lead 125, shown as containing a fuse 126, is connected to one terminal of the rheostat resistor 85, and a lead 127 connects the opposite terminal thereof, with one terminal of each of the closing coils 79 of the speed regulating relays 69. The opposite terminals of these closing coils are connected to ground, as shown.

It is thus apparent that, when the main switch 104 is closed, current will pass through, and will energize the closing coils 79, thus closing the contact elements 78. It is also apparent that the parallel rheostat circuit shown, through the contact buttons 86, contactor 89, slide rod 88, ground ribbon 93, rheostat housing 84 and a ground lead 129, will govern the supply of current to the closing coils 79, hence will control their degree of excitation and their tendency to close the contact elements 78. With the slide rod 88 in retracted position as shown, the least current will flow through the closing coils 79, and in advanced positions thereof, proportionately more current will flow through said coils.

Opposed to the closing coils 79 are the dropout coils 80, whose circuit is as follows: The field winding 76 of the governor generator 68 is excited by current through the lead 108, and a ground lead 130. One terminal of the armature winding is connected in parallel to a terminal of each of the dropout coils 80 by a lead 135 and by leads 136, each of which contains a variable resistor 137. The opposite terminal of each dropout coil is connected by a lead 138 to a common lead 139 containing a variable resistor 140, the lead 139 connecting with the opposite terminal of the armature winding 77.

It is thus apparent that a solenoid energizing circuit is provided, embodying the relay closing coils 79 and the relay contact elements 78 actu-

ated by the closing coils; that a solenoid de-energizing circuit is also provided, embodying the governor generator 68 and the dropout coils 80, which oppose the closing coils 79 and tend to open the contact elements 78; and that, depending upon the balance between these circuits, more or less energization of the solenoid coil 38, hence more or less supply of fuel to the engine, is provided. The individual variable resistors 137 will be pre-adjusted to cause opening and closing of the contact elements 78 in any desired sequence, while the single variable resistor 140 common to the whole de-energizing circuit is provided to prevent burning out of the dropout coils 80.

In operation, and with the rheostat 70 at a given setting, as the load on the engine increases, the speed of the governor generator 68 will tend to slacken, hence the de-energizing circuit will oppose the energizing circuit to a lesser degree and will result in the closing of one or more open contact elements 78. This overly compensates for a weaker current from the starter-generator 67, hence energizes the solenoid coil 38 to a greater degree. This, in turn, will result in a greater fuel supply to the engine to compensate for the greater load. It will be apparent that the governing effect of the de-energizing circuit will operate in reverse as the load is decreased, to supply less fuel to the engine to maintain constant speed under the lighter load.

It is thus apparent that a fuel injection system has been provided which accurately and rapidly adjusts the fuel supply in accordance with load requirements, and that adjustable or variable fuel pump elements have been minimized.

While I have shown the preferred form of my invention, it is to be understood that various changes may be made in its construction by those skilled in the art without departing from the spirit of the invention as defined in the appended claims.

I claim:

1. A fuel pump system for an internal combustion engine, comprising a fuel pump operable by the crankshaft of an engine and including a fuel pump cylinder and a fuel pump piston reciprocable therein, a fuel displacement pump including a displacement cylinder and a displacement piston reciprocable therein, means communicating said cylinders whereby fuel may be recycled between said cylinders on reciprocation of said fuel pump piston, means including a solenoid coil for urging said displacement piston to closed position, and means including a solenoid energizing circuit and a solenoid de-energizing circuit responsive to engine speed for controlling said last mentioned means and governing the stroke of said displacement piston.

2. In a fuel pump system for an internal combustion engine, comprising a reciprocating fuel supply pump, a reciprocating fuel displacement pump, means communicating said pumps to reciprocate said displacement pump and displace fuel by recycling between said pumps, the improvement which comprises electrical means associated with said displacement pump to control and vary the stroke thereof, and an electrical circuit responsive to engine speed for varying the energization of said electrical means.

3. A fuel pump system for an internal combustion engine, comprising a reciprocating fuel supply pump, a reciprocating fuel displacement pump including a displacement piston, means communicating said pumps whereby reciprocation of said supply pump tends to cause recipro-

cation of said displacement pump and recycling of fuel between said pumps, a solenoid coil operable to urge said displacement piston to closed position, an electrical circuit for energizing said coil and an opposed electrical circuit responsive to engine speed for de-energizing said coil.

4. The system of claim 3, wherein said energizing circuit includes and is operable to close a contact element and said de-energizing circuit is operable to open said contact element.

5. A fuel pump system for an internal combustion engine, comprising a reciprocating fuel supply pump including a fuel supply piston operable by the crankshaft of an engine, a reciprocating fuel displacement pump including a displacement piston, means communicating said pumps to reciprocate the displacement pump and to displace fuel from the fuel supply pump by recycling fuel between said pumps, stroke governing means urging said displacement piston to closed position, said stroke governing means including electromagnetic means, and means for controlling energization of said electromagnetic means comprising an energizing circuit and a

de-energizing circuit, said de-energizing circuit being responsive to engine speed and acting in opposition thereto.

6. The system of claim 5, wherein said electromagnetic means is a solenoid coil, said energizing circuit includes a plurality of relay contacts, and co-operating relay closing coils, and said de-energizing circuit includes a generator operable by the engine crankshaft and a plurality of drop-out coils complementary and opposed to said closing coils.
